UNITED STATES PATENT OFFICE.

HENRY BRACHTL, OF CHICAGO, ILLINOIS, ASSIGNOR TO ASSOCIATED ENGINEERS COMPANY, OF CHICAGO, ILLINOIS.

CABLE-BRACKET.

1,335,553.

Specification of Letters Patent. Patented Mar. 30, 1920.

Application filed June 6, 1918. Serial No. 238,496.

To all whom it may concern:

Be it known that I, HENRY BRACHTL, a citizen of the United States, residing at Chicago, in the county of Cook and State 5 of Illinois, have invented a certain new and useful Improvement in Cable-Brackets, of which the following is a full, clear, concise, and exact description, reference being had to the accompanying drawings, forming a 10 part of this specification.

My invention relates to cable brackets or supports and has for its object the provision of a bracket of this nature which is easily and readily attachable to suitable means 15 of support such as a manhole wall or the wall of a house, and which is provided with suitably formed means adapted to receive a saddle or other device for supporting a cable.

20 One of the objects of my invention is the provision of a device of the nature described in which the back portion and the arm portion are provided with means whereby they may be readily mounted together or separated, as may be required.

25 A further object of my invention is the provision of an arm portion for the bracket which is of such a nature that the arm portion clears a cable mounted below the arm portion upon a second arm portion.

30 A further object of the invention is the construction of an arm portion in a very simple and highly efficacious manner.

In one form of the invention, I find it 35 particularly desirable to construct the arm portion of bent piping so formed at its extremities to coöperate with the back portion and inter-lock therewith. In thus constructing the arm portion of the material 40 suggested it is very substantial and unbreakable.

I will describe the preferred form which my invention may take more in detail by referring to the accompanying drawing illustrating such embodiment, in which—

Figure 1 is a side view partly in section of my improved device;

Fig. 2 is a front view thereof;

Fig. 3 is a sectional view on line 3—3 of 50 Fig. 1, and

Fig. 4 is a sectional view on line 4—4 of Fig. 1.

55 My improved device consists of the back portion 10 which through the agency of bolts 11, 11 may be suitably mounted in place upon a wall 12. The back portion, as

more clearly apparent from Figs. 3 and 4, is constructed of one of the commercial shapes known as channels and is provided with a plurality of holes 13 therethrough. 60 The general outline of these holes is circular except that radially arranged notches 14, 14 project upwardly and downwardly therefrom. These holes 13 are of such a nature that they will accommodate both the 65 upper and lower legs of the arm portion 15 of my improved bracket. This arm portion, as stated, has two legs, respectively, the legs 16 and 17. The leg 16 is substantially straight and is adapted to support the saddle or saddles 18, these saddles having projecting downwardly therefrom clamping elements 19, 19, preferably spring-like in character, which encircle the leg 16 and hold the saddles 18 in place. These saddles 18 then 70 support the cable 20, indicated in dotted lines in Fig. 1. The arm portion 15 is made of pipe bent into the required form, as shown. The free extremity of the leg 16 is formed by having the extremity 21 pressed 75 substantially into flat, rectangular form, thereby providing shoulders 22, 22, which project outwardly from the leg portion 16, the immediately adjacent part of the leg 16 being held by a mandrel during the process 80 of forming so that the part of the leg immediately adjacent the rectangular extremity 21 retains its substantially rounded characteristics so as to fit within the hole 13. The rectangular extremity 21 is of such a 85 size that it may be introduced through the radial extensions 14, 14 when the leg portion 16 is swung ninety degrees from the position it occupies in Fig. 1. If the leg 16 is then returned to the position it occupies 90 in Fig. 1, the shoulders 22, 22 abut against the back portion or channel 10, thus to prevent removal of the leg 16. The extremity of the leg 17 remains substantially rounded, but near the extremity I provide an up-set 95 portion 23 forming an annular ridge of a size larger than the hole 13. The ridge 23 coöperates to limit the inward movement of the extremity of the leg 17, as more clearly apparent from Figs. 1 and 4.

In order to mount the bracket in position therefore all that is necessary is to swing it ninety degrees from its vertical position, whereupon the rectangular flattened portion 21 may be inserted through the hole 13 with 100 its radial extensions 14; thereupon the arm portion 15 is swung into its vertical posi- 110

tion and the free extremity of the leg 17 inserted into one of the holes 13 provided in the back portion 10, the annular enlargement 23 limiting the inward movement of this leg. The leg portion 17 is bent, as shown in Fig. 1, so that it may clear a cable mounted upon the arm portion directly beneath the arm portion 15.

In Fig. 1, I likewise show an arm portion 15^a having legs 17^a and 16^a. The extremities of the legs 16^a and 17^a are constructed exactly the same as the extremities of the legs 16 and 17, the arm portion 15^a however being of a smaller type than the arm portion 15, being constructed simply for the support of one cable instead of two.

From what has been thus described the nature of my invention will be readily clear to those skilled in the art.

Having thus described one form which my invention may take, what I claim as new and desire to secure by Letters Patent is:

1. A cable bracket having a back portion and an arm portion, said arm portion consisting of a pipe bent substantially V-shaped, a saddle, means to secure the saddle to said arm portion, openings of special form provided in said back portion, one of the legs of the said arm portion having a widened extremity adapted to interlock with said openings and prevent removal of said leg portion when inserted through one of said openings and rotated into proper position, and an upset portion forming an annular ridge on the other leg portion to limit the penetration of said leg portion through its coöperating opening in the back portion.

2. A cable bracket having a back portion and an arm portion, said arm portion consisting of a member substantially V-shaped, cable holding means secured to one leg of the arm portion, openings of special form provided in said back portion, one of the

legs of the said arm portion having a widened extremity adapted to interlock with said holes and prevent removal of said leg portion when inserted through said hole and rotated into proper position, and means on the other leg portion to limit the penetration of said leg portion through its coöperating hole in the back portion, the lower one of the legs of said arm portion being bent inwardly intermediate its length.

3. A cable bracket having a back portion and an arm portion, said arm portion consisting of a pipe bent substantially V-shaped, openings provided in said back portion, formed extremities provided upon the free extremities of the legs of said arm portion to interlock with the openings in said back portion, the lower one of the legs of said arm portion being bent inwardly intermediate its length, and a saddle having means for attachment to the upper leg of said arm portion.

4. A cable bracket having a back portion and an arm portion, said arm portion consisting of a pipe bent substantially V-shaped, openings of special form provided in said back portion, one of the legs of said arm portion having a widened extremity adapted to interlock with said holes and prevent removal of said leg portion when inserted through said hole and rotated into proper position, means on the other leg portion to limit the penetration of said leg portion through its coöperating hole in the back portion, the lower one of the legs of said arm portion being bent inwardly intermediate its length, and a saddle having means for attachment to the upper leg of said arm portion.

In witness whereof, I hereunto subscribe my name this 15th day of May, A. D. 1918.

HENRY BRACHTL.
